UNITED STATES PATENT OFFICE.

MAXIMILIAN H. KORN, OF TEANECK, NEW JERSEY.

PIER-SHED DOOR.

Application filed August 18, 1925. Serial No. 50,964.

This invention relates to pier shed doors and has for an object to provide an improved construction wherein a strong door is presented while means are provided for readily moving the door out of the way whenever desired.

Another object of the invention is to provide a door wherein the same is formed in sections and associated with mechanism for readily raising the sections to a point above the door opening.

A further object of the invention, more specifically, is to provide a sectional pier shed door with means for readily raising the same partially or completely and with the parts so formed that when the door is closed the various sections will be properly braced to take care of any strain that might be brought to bear thereon.

An additional object, more specifically, is to provide a pier shed door and form the same into sections with suitable guiding runways and guiding members co-acting therewith whereby the sections may be quickly and easily elevated from a closed position to an upward position out of the door opening.

In the accompanying drawings—

Figure 1 is a rear view of a door disclosing an embodiment of the invention, the same being shown in connection with certain beams and parts of the pier shed construction.

Figure 2 is an enlarged sectional view through Figure 1, approximately on line 2—2, the door and certain other parts being shown in elevation and the lower part being cut off.

Figure 2^a is a view showing the lower part of the door structure illustrated in Figure 1.

Figure 3 is a top plan view of the lifting mechanism and associated parts shown in Figure 1, the same being an enlarged view and illustrating the lifting mechanism of adjacent doors.

Figure 4 is an enlarged fragmentary view showing the interior of one end of one of the door sections illustrated in Figure 1.

Figure 5 is a sectional view through Figure 4 on line 5—5.

Figure 6 is an enlarged fragmentary sectional view showing the structure of adjacent sections and how the upper section is guided until it has moved a certain distance.

Figure 7 is an enlarged fragmentary view showing a connection of the lifting cable to the respective door sections.

Figure 8 is a view similar to Figure 2 but showing a modified form thereof.

Figure 8^a is a view similar to Figure 2^a but showing the lower part of the structure 60 illustrated in Figure 8.

Figure 9 is a fragmentary top plan view of one end of the structure shown in Figure 8.

Figure 9^a is a detail fragmentary perspective view of the lower part of some of the doors shown in Figure 8.

Referring to the accompanying drawings by numerals, 1 indicates the door jamb of the door of a pier shed and 2 certain upper beams which hold the jamb 1 in place and which also act as connecting and supporting means for other parts including the roof or second floor of the shed. The structures just described are old and well known and, therefore, form no part of the present invention except in combination with the door 3. This door is made up of a number of sections 4 and said sections are individually raised by cables 5 and 6 mounted to be 80 wound upon the respective stepped drums 7 and 8 which act with other parts as lifting means for raising the sections to a position out of the door opening.

As indicated in Figure 3, there is provided a pair of drums 7 and 8 for each door and each of these drums is rigidly connected to a shaft 9 which is adapted to be manually rotated for actuating the drums 7 and 8. This manual structure is shown in Figures 90 1 and 3 and includes a worm wheel 10 rigidly secured to shaft 9 and meshing continually with the worm 11 carried by the shaft 12. The shaft 12 has a chain wheel 13 rigidly secured thereto and over which the chain 14 passes as the chain is moved. This chain wheel is of the usual type capable of receiving the links of chain 14 and interlocking therewith so that when one run of the chain is pulled the chain will rotate the wheel 13 and parts connected therewith. In order to counterbalance the weight of the various sections 4 and thereby permit the chain 14 to be moved manually with little trouble, a drum 15 is rigidly secured to shaft 9 and on this drum is wound a cable 16, which cable passes over suitable pulleys 17 and the end of the cable 16 is secured to a suitable weight 18. The cable is extended in the manner shown in Figure 3 in order 110 that the weight 18 may be in the framework of the jamb 1 though it could be placed at

any other convenient point without departing from the spirit of the invention.

By reason of the stepped formation of the drums 7 and 8, the various sections 4 are raised independently and at different speeds so that they will all become nested at the top at the same time. The largest portion of the drum 7, for instance, carries the cable which is connected with the lowermost section 4 and the second largest portion of the drum is connected with the second section from the bottom. This idea is carried throughout the various structures and the parts are properly proportioned so that when the chain 14 is pulled properly the various sections will all immediately begin to move upwardly and at different speeds but at such speeds that they will all be nested at the top at the same time.

In Figures 4 and 5, certain details of the various sections 4 are shown. From these figures it will be observed that these doors are formed from a suitable framework 19, to which a sheet metal covering 20 is secured. The framework 19 includes the top and bottom angle irons 21 and 22. Arranged near the top of each section 4 is a stub shaft 23 bolted or otherwise secured to the frame 19 and on these stub shafts are arranged rollers 24. Near the bottom and at each end of the various sections 4 there are arranged brackets 25, each bracket carrying a roller 26. The pintle or stub shaft 27 extends through bracket 25 and roller 26 and also through the roller bearing 28 which co-acts with the roller 24 for guiding the section as it moves up the respective grooves 29. It will be noted that all these guiding grooves except the one for the top section are inclined from the bottom to the top and that all except the top one have short bends at the bottom and near the top. The ordinary rollers 24 and 28 are intended to move in these grooves or rather these spaced bars acting as guides, the arrangement being shown particularly in Figure 3.

As indicated in Figures 2 and 2^a, the various guiding channels or grooves 29 stop at the different points 29' except the channel 50 running to the bottom and in order to accommodate this matter there is provided a roller 26 at the bottom of each of the sections 4 except the lowermost section. The rollers 26 engage the side of the jamb 1 as soon as the guiding roller 28 leaves its channel 29. The upper guiding roller 24 always remains in the guiding channel 29. In this way, the sections are readily guided to a closed position or to an open position and friction is reduced to a minimum while at the same time providing a tight door against the weather. In order to take care of the action of wind, there is provided what may be termed wind locks as shown in Figures 1 and 6. These consist of strips of metal 30 coact-

ing with the various rollers 31 carried by brackets 32, which brackets are bolted or otherwise secured to the lower part of all of the sections 4 except the lowermost section. The metal strip 30 is preferably somewhat resilient and, therefore, continuous to act to press the lower part of the door sections tightly against the jamb when the door is closed. When the door is being opened, the various sections may pass each other as they are nested at the top by reason of the flare 30'. Connected to the various sections 4 are cables 5 and 6, said cables being connected preferably to the upper edge of the sections through suitable U-shaped members 33 (Figure 7). A turn buckle 34 is also preferably used and interposed between the end of the cables and the U-shaped member 33 whereby a fine adjustment may be secured and in this way the various sections caused to function easily and accurately.

In Figures 8 and 9, a modified structure is shown wherein the various sections 4' are arranged at an angle. These sections are preferably constructed the same as section 4 of Figure 1 but the wheels or guiding rollers 26 and 31 are eliminated as the various pins 35 and 36 are continually positioned in the guides 37, which guides extend from a position above the door opening to the bottom of the plates where the particular section of door is to be positioned. It will be noted that these guides are at an angle from top to bottom and that the various sections 4' move at an angle and remain at an angle at all times though the effective plane of the door when closed is vertical. A pin 38 is arranged at each end of each of the sections 4' except the top section, said pins being arranged near the upper edge of the respective sections and projecting far enough to engage the next superimposed section and raise the same when the lower section is being raised. It will thus be noted that when the lower section is raised a short distance the second section from the bottom will also be raised and as the various sections are gradually moved toward the top the higher sections are gradually collected until finally all of the sections are nested together at a point above the door opening.

As the lower sections collect and raise the next upper sections it is necessary to provide only a single pair of cables 39 instead of two cables 5 and 6 as shown in Figure 1 for each section. A cable or chain 39 is connected to the lowermost section 4' near the respective ends thereof and these cables or chains are wound upon suitable drums 40 and as they are wound the various sections will be collected successively and moved to the position shown in dotted lines in Figure 8. A shaft 41 connects the respective drums 40 so that when this shaft is rotated both drums will be operated and the sections raised evenly. A small drum 42

- is rigidly secured to the shaft 41, said drum accommodating a cable or chain 43 which passes over suitable pulleys 44 and is connected with a counterbalancing weight 45.
- 5 Preferably there is a counterbalancing weight, chain and associated parts near each end of shaft 41. A worm wheel 46 is rigidly secured to shaft 41 and meshes continually with the worm 47 carried by shaft 48. The
- 10 shaft 48 carries a chain wheel 49 adapted to receive the chain 50 whereby when one run of this chain is pulled the parts will be actuated for rotating shaft 41 and either lift or lower the various sections 4'. In this
- 15 form of the invention the usual vertical jamb 1 must be supplemented by plates or fittings 51 so that the ends of the various sections 4' may properly fit these plates to produce a tight door structure. In this form of the
- 20 invention, as well as the preferred form, the door has the distinct advantage of not encroaching on the desired freight space within the pier or railroad shed. By reason of the vertical or substantially vertical movement of the sections and also their position, much less space is taken than with doors now in common use.
- A large sized door of the kind generally required in the sides of steamship-piers or
- 30 railroad freight sheds, is essential for business purposes and, in fact, makes up usually all or most of the side of the shed. Doors for this purpose heretofore were made to turn or fold, whereas in the present invention the door is made in sections of a desired size and is lifted substantially vertically to a position out of the way, thus leaving the door opening free. In constructing the various doors, and particularly the sections 4 and 4', a number of
- 35 sections or leaves are such that all sections shall be no higher than the clear head room above the door room. Also, by forming the door into the sections described, the door
- 40 may be easily opened or closed. In this connection, it will be noted that the worm and worm gear provided above the door opening and acting with a suitable counter-weight makes the door very easily operated
- 45 and also presents a structure whereby the door is locked either in open or closed position. Also, this structure permits glazed sashes to be used. When the door is fully open, the various sections are nested at a
- 50 point slightly above the door opening, and when the door is closed all sections are flush on the outside face and represent a proper closure for the door opening.
- It will be noted that by the use of a
- 55 counterweight, the door very easily operates and since all the door sections move simul-
- taneously, a hundred per cent counter-balance is possible, on account of which, the door not only operates easily but will remain stationary in any position of opening
- 60 or closing. When the door is closed, the sections are all arranged in a vertical line and not offset inwardly or outwardly and, consequently, take up a minimum space.
- 65 The guides which guide the various sections are provided with two bends, one at the bottom and one near the top except for the top section, and the parts between these bends are straight but inclined slightly from the vertical. This structure, therefore, results in a door having the sections in the same vertical plane when the door is closed
- 70 and in the same horizontal plane when the door is fully open.
- 75 It is understood that although manually operated doors are shown and described, motor operated doors can also be used without departing from the spirit of the invention.
- Having thus described my invention, what I claim is:
1. In a shed door, a door body formed with a plurality of sections, each section having a stiffened frame, a covering body therefor, a pin at each end acting as guides, a rotatable member mounted on each pin, locking rollers intermediate the ends, and wind locks on the opposite side to said rollers but in line therewith, the wind locks of one section co-acting with the rollers of the next adjacent section.
2. A shed door comprising a plurality of sections of not less than four in number arranged one directly above the other when the door is closed for presenting a flush outside face, elevating means for independently moving the sections to an elevated position when the door is to be opened, said means causing the sections to be nested at a point above the door, means for causing each of said sections first to swing out of a vertical plane and then move upwardly while inclined, and a counterbalancing structure for permitting the sections to be lifted with a minimum amount of power.
- 100 3. In a door, a plurality of slidable door sections adapted to be collapsed at one margin of the door opening but capable of being moved to a position to extend across the door opening and disposed in longitudinal alinement, rollers projecting from one end of each section, and resilient arms projecting from the adjacent end of each section and engaging the rollers to retain the sections in longitudinal alinement against
- 105 vibration.

MAXIMILIAN H. KORN.
